LOCK

Percy M. Brown, Tenafly, N. J., assignor to Anchor Products Company, North Bergen, N. J., a partnership

Application December 24, 1948, Serial No. 67,170

8 Claims. (Cl. 292—124)

1

This invention relates to locks.

An object of this invention is to provide a lock comprising two parts, said parts having interlocking means and one of the parts being provided with a ball projecting through an opening in a ball socket, the construction being such that when the ball is depressed by a finger, the interlocking parts will release so that the two parts may be separated, the construction being such, furthermore, that the two parts may be readily interlocked by merely interfitting the parts together, that is, by moving said parts toward each other.

Still another object of this invention is to provide in a lock of the character described, a spring pressed latch which may be retracted up by pressing a ball projecting through an opening in a ball socket.

Yet a further object of this invention is to provide a strong, rugged, and durable lock of the character described which may have application to luggage, jewelry, pocketbooks, automobiles, men's and women's wrist watches, or any other application where it is desired to quickly lock two objects together by merely pressing one against the other, and where it is desired to provide for easy release by merely pressing a ball.

Still another object of this invention is to provide a strong, rugged, durable, and compact lock of the character described which shall comprise few and simple parts, which shall be relatively inexpensive to manufacture, which shall be smooth and positive in operation, easy to manipulate, and yet practical and efficient to a high degree in use.

Other objects of this invention will in part be obvious and in part hereinafter pointed out.

The invention accordingly consists in the features of construction, combinations of elements, arrangement of parts and method steps which will be exemplified in the construction herein-after described, and of which the scope of invention will be indicated in the following claims.

In the accompanying drawings in which is shown various illustrative embodiments of this invention:

Fig. 1 is a longitudinal, cross-sectional view of the lock embodying the invention taken on lines 1—1 of Fig. 2, and illustrating one application of said lock;

Fig. 2 is a cross-sectional view taken on line 2—2 of Fig. 1;

Fig. 3 is a cross-sectional view taken on line 3—3 of Fig. 2; and

Fig. 4 is a side elevational view of the lock embodying the invention.

2

In the drawing, like reference numerals indicate like parts. The lock may comprise two parts designated by numerals 11 and 12, which parts are to be locked together. The part 12 comprises a plate 13 formed with a central upwardly extending cylindrical or tubular wall 14. The wall 14 is formed at its upper end with an annular inwardly extending flange or lip 15 for the purpose hereinafter appearing. The plate 13 may be provided with a plurality of bent-back prongs 16 adapted to pierce or penetrate a sheet or article 18 to which the plate 13 is attached.

The part 11 comprises a member 20 having a top wall 21 of generally rectangular shape. Extending from wall 21 are a pair of parallel end walls 22, and a pair of parallel side walls 23. Extending from the walls 22 are bent-back prongs 24 which may be used to penetrate a sheet or article 29 to which member 20 is fixed. As will be noted hereinafter, the sheets 18 and 29 will be locked together by means of the interlocking members 11 and 12. The prongs 24 and 16 merely illustrate one application of the lock, it being understood that member 13 may be fixed to any article in any suitable manner, and member 21 may be fixed to any other article in any suitable manner where it is desired to lock such articles together.

It will now be understood that member 20 is in the form of a case open at the bottom. The top wall 20 is formed with an upwardly extending annular ball socket 30 formed with an opening 31 at the top. The socket 30 is somewhat part-spherical and tapers toward the opening 31. Disposed within the bottom of the case 20 is a member 40 having a wall 41 fitted within the case and fixed thereto in any suitable manner. Wall 41 may be welded, pressed, or soldered to the lower end of member 20, or otherwise fixed thereto by any known means. Extending downwardly from wall 41 is a cylindrical or tubular portion 42 which may surround and receive or telescope with the cylindrical portion 14 of member 13. It will now be understood that between wall 41 of member 40 and walls 21, 22, and 23 of the case 20 is a compartment 45.

Slidably mounted within said compartment is a slider 46. The same comprises a substantially rectangular plate formed at one end with a longitudinal central slot 47. The slider 46 is of less length than the compartment 45 so that it may reciprocate from left to right. Disposed within the compartment 45 is a coil compression spring 48 projecting into the slot 47 and interposed be-

tween one end of the slot and the adjacent end wall 22. The spring 48, thus, tends to move the slider 46 to the right into engagement with the opposite end wall 22. Extending downwardly from the slider 46 is a latch 50. Said latch has a tapered or rounded lower end projecting down through the opening formed by annular lip 15. The latch 50 is formed with a horizontal slot 51. When the slider 46 is moved to the right by spring 48, the lip 15 will enter the slot 51 and thus lock member 11 to member 12. However, should the slider 46 be moved to the left, looking at Fig. 1, the latch 50 will become disengaged from the lip 15 so that members 11, 12 may be separated. It will be noted that the latch 50 is of less diameter than the opening formed by the lip 15.

The top surface of slider 46 is formed with a part-spherical depression or socket 55. Disposed within the socket 30 is a ball 56. Opening 31 is of less diameter than ball 56. The depression of socket 55 may be of substantially the same radius as the ball 56, and said ball will project through opening 31 in the socket 30. Spring 48 will press the slider 46 to the right causing an edge of the socket 55 to press against the ball and push the ball up so that it projects partly through opening 31. In such condition, the ball will not be seated within the socket 55. However, should the ball 56 be depressed by a finger, the slider 46 will be cammed to the left, seating the ball 56 within the socket 55, and releasing the latch 50 from the lip 15, and thus releasing the locking engagement between parts 11 and 12. The two parts 11 and 12 may then be separated.

When pressure is relieved from the ball 56, it will then be pressed outwardly, but will, of course, be held in the position shown in Fig. 1, partly projecting through socket 30. In such position, if the tubular portion 14 were pressed into the tubular portion 42, the lip 15 would engage the bottom curved surface of the latch 50 and move the slider 46 sufficiently to the left to permit the lip 15 to rise to the level of the slot 51. During such action, the slider 46 is moved to the left compressing the spring 48, and when the lip 15 reaches the level of slot 51, the compressed spring 48 will again move the slider 46 to the right so that the latch 50 will engage the lip 15, and the two parts 11 and 12 will then be locked together.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A lock comprising a part having a tubular portion formed with an annular inwardly extending lip forming a central opening, a second part comprising a casing having a tubular portion telescoping with the tubular portion of the first part, a slider within said casing, spring means in the casing to move the slider in one direction, a latch on said slider projecting into said tubular portion of said casing, said latching having a slot engageable with said lip, a ball retaining socket on said casing, a ball within said socket and said slider being formed with a recess into which the ball partly projects, said ball partly projecting beyond

said ball retaining socket, and being depressible for moving the slider against said spring to release said latch from said lip.

2. A lock comprising two parts, one part comprising a flat wall, a tubular portion extending from said wall, and formed with a lip, the second part comprising a case having a top wall and downwardly extending side and end walls, said top wall being formed with an upwardly extending ball retaining socket formed with an opening through which the ball partly projects, a bottom wall closing the bottom of the case and formed with a downwardly projecting tubular portion adapted to telescope with the tubular portion of the first part, a slider slidably mounted within said case, spring means in said case to urge said slider in one direction, said slider being formed with a downwardly projecting latch formed with a slot adapted to engage said lip, said slider being formed in its upper surface with a part-spherical recess, and a ball within said ball retaining socket, partly projecting into said recess.

3. A lock comprising two parts, one part comprising a flat wall, a tubular portion extending from said wall, and formed with a lip, the second part comprising a case having a top wall and downwardly extending side and end walls, said top wall being formed with an upwardly extending ball retaining socket formed with an opening through which the ball partly projects, a bottom wall closing the bottom of the case and formed with a downwardly projecting tubular portion adapted to telescope with the tubular portion of the first part, a slider slidably mounted within said case, spring means in said case to urge said slider in one direction, said slider being formed with a downwardly projecting latch formed with a slot adapted to engage said lip, said slider being formed in its upper surface with a part-spherical recess, and a ball within said ball retaining socket, partly projecting into said recess, and means on said parts for attachment to articles to be locked together.

4. A lock comprising two parts, one part comprising a flat wall, a tubular portion extending from said wall, and formed with a lip, the second part comprising a case having a top wall and downwardly extending side and end walls, said top wall being formed with an upwardly extending ball retaining socket formed with an opening through which the ball partly projects, a bottom wall closing the bottom of the case and formed with a downwardly projecting tubular portion adapted to telescope with the tubular portion of the first part, a slider slidably mounted within said case, spring means in said case to urge said slider in one direction, said slider being formed with a downwardly projecting latch formed with a slot adapted to engage said lip, said slider being formed in its upper surface with a part-spherical recess, and a ball within said ball retaining socket, partly projecting into said recess, and means on said parts for attachment to articles to be locked together.

5. A lock comprising two parts, one part comprising a flat wall, a tubular portion extending from said wall, and formed with a lip, the second part comprising a case having a top wall and downwardly extending side and end walls, said top wall being formed with an upwardly extending ball retaining socket formed with an opening through which the ball partly projects, a bottom wall closing the bottom of the case and formed with a downwardly projecting tubular portion adapted to telescope with the tubular portion

of the first part, a slider slidably mounted within said case, spring means in said case to urge said slider in one direction, said slider being formed with a downwardly projecting latch formed with a slot adapted to engage said lip, said slider being formed in its upper surface with a part-spherical recess, and a ball within said ball retaining socket, partly projecting into said recess, the bottom of said latch being curved, said lip being annular, forming a central opening through which said latch may project.

6. A lock comprising two parts, one part comprising a flat wall, a tubular portion extending from said wall, and formed with a lip, the second part comprising a case having a top wall and downwardly extending side and end walls, said top wall being formed with an upwardly extending ball retaining socket formed with an opening through which the ball partly projects, a bottom wall closing the bottom of the case and formed with a downwardly projecting tubular portion adapted to telescope with the tubular portion of the first part, a slider slidably mounted within said case, spring means in said case to urge said slider in one direction, said slider being formed with a downwardly projecting latch formed with a slot adapted to engage said lip, said slider being formed in its upper surface with a part-spherical recess, and a ball within said ball retaining socket, partly projecting into said recess, the bottom of said latch being curved, said lip being annular, forming a central opening through which said latch may project, the diameter of said ball being substantially similar to the diameter of said recess.

7. A lock comprising a part having a tubular portion, formed with an annular inwardly extending lip forming a central opening, a second part comprising a casing having a tubular portion telescoping over the tubular portion of the first part and a slider slidably mounted within said casing for movement in opposite directions, spring means in the casing to move said slider in one of said directions, a latch on said slider projecting into said tubular portion of said casing and movable into said opening, said latch having a slot engageable with said lip, a depressible member within said casing, said casing having an opening exposing a portion of said depressible member, said slider being formed with a cammed recess, cammed means on said depressible member adapted to engage said cammed recess when

said depressible member is depressed, for sliding of said slider against said spring, to disengage said latch from said lip, and said spring being adapted, when said depressible member is released, to slide said slider for engaging the latch with the lip and raising said depressible member.

8. A lock comprising a part having a tubular portion, formed with an annular inwardly extending lip forming a central opening, a second part comprising a casing having a tubular portion telescoping over the tubular portion of the first part and a slider slidably mounted within said casing for movement in opposite directions, spring means in the casing to move said slider in one of said directions, a latch on said slider projecting into said tubular portion of said casing and movable into said opening, said latch having a slot engageable with said lip, a depressible member within said casing, said casing having an opening exposing a portion of said depressible member, said slider being formed with a cammed recess, cammed means on said depressible member adapted to engage said cammed recess when said depressible member is depressed, for sliding of said slider against said spring, to disengage said latch from said lip, and said spring being adapted, when said depressible member is released, to slide said slider for engaging the latch with the lip and raising said depressible member.
- 10 15 20 25 30 35 40 45 50
9. A lock comprising a part having a tubular portion, formed with an annular inwardly extending lip forming a central opening, a second part comprising a casing having a tubular portion telescoping over the tubular portion of the first part and a slider slidably mounted within said casing for movement in opposite directions, spring means in the casing to move said slider in one of said directions, a latch on said slider projecting into said tubular portion of said casing and movable into said opening, said latch having a slot engageable with said lip, a depressible member within said casing, said casing having an opening exposing a portion of said depressible member, said slider being formed with a cammed recess, cammed means on said depressible member adapted to engage said cammed recess when said depressible member is depressed, for sliding of said slider against said spring, to disengage said latch from said lip, and said spring being adapted, when said depressible member is released, to slide said slider for engaging the latch with the lip and raising said depressible member, the lower end of said latch being cammed whereby upon inserting said latch within said opening and telescoping the tubular portion of said casing over the tubular portion of the first part, said cammed surface of said latch will engage said lip for moving said slider against said spring until the lip registers with the slot in the latch to permit the spring to then move the slider in an opposite direction for permitting the lip to enter into said slot.
